Patented Dec. 26, 1972

225,605

GRASS TRIMMER

John S. Doyel, 404 W. 20th St., Brooklyn, N.Y. 10011

Filed Feb. 19, 1971, Ser. No. 117,172

Term of patent 14 years

Int. Cl. D8—03

U.S. Cl. D8—8

Fig. 1.

Fig. 2.

FIG. 3.

FIG. 4.

FIG. 5.

FIG. 1 is a top plan view of the grass trimmer, showing my new design.

FIG. 2 is a side elevational view of the grass trimmer.

FIG. 3 is a bottom plan view of the grass trimmer.

FIG. 4 is a side elevational view of the grass trimmer viewed from the side opposite that shown in FIG. 2.

FIG. 5 is a front elevational view of the grass trimmer. I claim:

The ornamental design for a grass trimmer, as shown and described.
